Des. 212,081
Patented Aug. 27, 1968

212,081

TELEPHONE BOOTH

Henry Dreyfuss, South Pasadena, Calif., and James L. Fischer, Carmel, and Norris R. Hall, Indianapolis, Ind., assignors to Bell Telephone Laboratories, Incorporated, Murray Hill, N.J., a corporation of New York

Filed Dec. 4, 1967, Ser. No. 9,624

Term of patent 14 years

(Cl. D13—1)

FIG. 1

FIG. 2

FIG. 3

FIG. 1 is a front perspective view of a telephone booth in accordance with the invention;

FIG. 2 is a rear perspective view of the booth shown in FIG. 1;

FIG. 3 is a top view of the booth shown in FIG. 1, drawn to an enlarged scale;

FIG. 4 is a front view of the booth shown in FIG. 1, drawn to an enlarged scale; and

FIG. 5 is a side view of the booth shown in FIG. 1, drawn to an enlarged scale.

The telephone set, the associated shelf, the telephone directories and the printed sign, all shown in broken lines, are for illustrative purposes only.

We claim:

The ornamental design for a telephone booth, substantially as shown and described.
